UNITED STATES PATENT OFFICE.

ROBERT D. BONNEY, OF NORWOOD, PENNSYLVANIA, ASSIGNOR TO CONGOLEUM-NAIRN, INC., A CORPORATION OF NEW YORK.

SURFACE COVERING AND METHOD OF ORNAMENTING SAME.

Application filed December 31, 1927. Serial No. 243,924.

My present invention relates to surface coverings and to a process of ornamenting the same. More particularly does it relate to the ornamentation of flexible hard-surfaced floor coverings, whereby a color pattern is formed thereon, in a manner to cause such pattern to stand out in relief. The invention is especially applicable to the production of a flexible floor covering having a substantially smooth wearing surface formed by depositing layers of paint upon a suitable backing and having a color pattern thereon in imitation of hand-laid glazed ceramic tiling.

5

10

Essentially, the invention consists in ornamenting the surface of a suitable base, such as linoleum or asphalt saturated felt, by printing or coating or both, to form a color pattern thereon, certain portions or areas of such color pattern having a high gloss or luster, and certain other portions or areas of said 15 color pattern having substantially no luster or gloss, and the areas or portions having substantially no luster or gloss preferably being formed very slightly below the general surface 20 level of the goods.

In order that the invention may be clearly understood, I will describe in detail one specific embodiment thereof, namely, the ornamentation of a flexible, hard-surfaced 25 floor covering in imitation of hand-laid glazed ceramic tiling, and also the specific method of obtaining same. In this description, I shall refer to the accompanying drawing, in which:

30 Figure 1 illustrates a strip of floor covering embodying my invention, during the process of manufacture; and

Figure 2 is a sectional elevation on an enlarged scale, taken on the line 2—2 of Figure 1.

35 In carrying out my invention, I employ as a base, a strip of flexible floor covering material 1, having a smooth surface such as linoleum or asphalt saturated felt. In using the latter 40 material, the base is usually preliminarily coated upon both sides with a paint, varnish, or cellulose lacquer to seal in the asphalt saturant. According to the preferred 45 method, the base material is first uniformly 50 coated upon the side which is to subsequently form the wearing surface, with a colored paint layer 2, which is selected, in accordance with the color pattern, to serve 55 as a background or field color in imitation of the mortar joints of hand-laid ceramic

tiling. This paint is chosen to provide that characteristic essential to the invention, namely, that it shall possess substantially no luster or gloss when dry, and also to provide that characteristic of smooth, dense texture 60 which is requisite for serviceable wear.

The strip having thereon the coating or paint layer 2 of the characteristics defined, is dried in the usual manner. It is then passed through a block printing machine of the type 65 described and shown in Letters Patent No. 1,145,821, granted to William H. Waldron, July 6, 1915, in which there is a series of print blocks mounted on carriers having an intermittent reciprocating motion to and from 70 the material as the strip is moved through the machine. The print blocks are provided with raised patterns corresponding to the color pattern to be impressed, there being at least one block for each color to be printed. 75 These blocks are supplied with a paint of a color different from that employed in the coating 2, and, in contradistinction thereto, being of the enamel type and adapted to yield a high luster or gloss when dry. As the 80 blocks reciprocate, a plurality of variously colored paint layers, 3, 4, and 5, of tile-like configurations corresponding to the pattern, are deposited upon the coated strip. In the drawing, three kinds of color units or layers 85 are employed. The units 3 are alike in color as indicated by the horizontal lines. The units 4 are alike in color as indicated by the diagonal lines; and the units 5 are alike in color as indicated by the vertical lines. If 90 desired, however, the paint layers of tile-like configuration may be of the same color or different shades of the same color.

According to my invention, the variously colored paint layers, 3, 4, and 5, of tile-like 95 configuration, are non-contiguous and are so arranged as to leave visible in the completed color pattern, portions 6 of the lusterless coating 2 of such configuration as to simulate the mortar joints between the tiles. 100 This results in an ornamentation for floor covering in imitation of hand-laid glazed ceramic tiling, wherein the portions representing the tiles are formed of a layer of high gloss or lustrous paint, while the portions representing the mortar joints are formed of a layer of paint of substantially no luster or gloss. Furthermore, the layers of paint, 3, 4, 5, of tile-like configuration, being 105 deposited upon the lusterless coating 2, serve 110

to form a color pattern which, although substantially in one plane, is, nevertheless, in very slight physical relief, such relief being equivalent to the thickness of the paint 5 layers.

The color pattern formed in this manner, stands out strikingly, partially because of the slight actual physical relief of the tile-like portions, but principally because it is 10 optically accentuated by the variation in luster between the layers of paint simulating the tile elements and the layers of paint simulating the mortar joint between such tile elements. Such variation in luster or gloss 15 not only simulates natural variation of luster between the tiles and mortar in hand-laid glazed ceramic tiling, but so strongly creates the impression of a pattern formed in relief, that a flexible hard-surfaced floor 20 covering ornamented with a tile pattern according to my invention, appears to possess all the characteristics of hand-laid glazed ceramic tiling, including the recessed mortar joints between the tiles.

25 As distinguished from flexible hard-surfaced floor coverings which are actually embossed or recessed with a pattern, and, therefore, possess the disadvantages of collecting dirt in the grooved portion lying at the lower 30 levels and of susceptibility to cracking at these lower elevations due to reduced difference of thickness of the floor covering, my invention avoids these disadvantages, and provides for a floor covering of substantially 35 uniform thickness and possessing a substantially smooth wearing surface, while exhibiting the visual effect of a color pattern formed thereon in relief.

It will be apparent that certain modifications 40 may be made in the manner of carrying out my invention. Thus, if desired, the coating or layer 2 of non-lustrous paint, need not be applied over the entire surface of the strip, but may be printed thereon at such 45 points as it is to be visible in the final color pattern, leaving open spaces of tile-like con-

figurations, which will be subsequently filled with layers of variously colored paints of high gloss or luster. According to this practice, the color pattern is in reality formed in 50 a single plane, but, nevertheless, it possesses the illusory effect of being formed in relief, owing to the selected variation in luster or gloss between the layers of paint simulating the tile elements and the layer of paint simulating the mortar joints between such tile elements. 55

While it is apparent that my invention is particularly applicable to the ornamentation of floor coverings simulating hand-laid glazed ceramic tiling, the essentials thereof may likewise be employed in ornamentation with other patterns, and the invention is, therefore, not limited to its illustrated embodiment, but may be otherwise embodied 60 within the scope of the following claims.

Claims—

1. The method of ornamenting the surface of a flexible hard-surfaced floor covering, which comprises coating its surface with a 70 layer of paint having substantially no luster or gloss, and printing upon said coating with vari-colored paints of high luster or gloss figures of tile-like configuration, such tile-like figures being non-contiguous and arranged to leave visible in the completed color pattern a portion of the lusterless paint layer of such configuration as to simulate mortar joints between said tile-like figures. 75

2. The method of ornamenting the surface 80 of flexible hard-surfaced floor covering which comprises coating this surface with a layer of paint having substantially no luster or gloss, and printing figures upon said coating with vari-colored paints of high luster or gloss, and printing figures upon said 85 surface and arranged to leave visible in the completed color pattern portions of the lusterless paint layer.

In testimony whereof, I affix my signature.

ROBERT D. BONNEY.
